UNITED STATES PATENT OFFICE.

HARVEY A. MOYER, OF SYRACUSE, NEW YORK.

DESIGN FOR A BODY-LOOP FOR VEHICLES.

SPECIFICATION forming part of Design No. 30,418, dated March 28, 1899.

Application filed March 1, 1899. Serial No. 707,411. Term of patent 14 years.

To all whom it may concern:

Be it known that I, HARVEY A. MOYER, a citizen of the United States, and a resident of Syracuse, in the county of Onondaga, in the State of New York, have invented a new and original Design for Body-Loops for Vehicles, of which the following, taken in connection with the accompanying drawings, is a full, clear, and exact description.

In said drawings, Figure 1 is a perspective view of a body-loop, showing my design; and Fig. 2 is a transverse section on line X X in Fig. 1, viewed in the direction of the arrow.

The leading or material feature of my design consists of the arch or bow *a*, disposed in a vertical plane and formed with abrupt downward deflections *a' a'*, terminating with horizontal arms *b b*, extending from the same side of said arch or bow and perforated, as shown at *ccc*. From the opposite side of the

arch or bow *a*, at the central portion thereof, projects horizontally a web *d*, which extends part way the length of the arch and is curved correspondingly. The free edges of said web are beveled outward from bottom to top, as shown at *i*, and from the central portion of the longitudinal edge of the web projects a lip *e*, which is in the same plane with the web. Both the web and the lip projecting therefrom are perforated, as shown at *ll* in Fig. 1 of the drawings.

Having described my invention, what I claim as new, and desire to secure by Letters Patent, is—

The design for a body-loop for vehicles, as herein shown and described.

HARVEY A. MOYER. [L. S.]
